(57) **CLAIM**

The ornamental design for a base for a short side plate, as shown and described.

DESCRIPTION

FIG. 1 is a front elevational view of a base for a short side plate showing my new design;

FIG. 2 is a rear elevational view thereof;

FIG. 3 is a top front isometric view thereof;

FIG. 4 is a top rear isometric view thereof;

FIG. 5 is a right side elevational view thereof; and,

FIG. 6 is a bottom plan view thereof.

The left side elevational view is a mirror image of FIG. 5.

The top plan view is a mirror image of FIG. 6.
